UNITED STATES PATENT OFFICE.

GURDON CONKLING, OF GLENS FALLS, NEW YORK.

MAGNETIC SEPARATOR.

SPECIFICATION forming part of Letters Patent No. 402,904, dated May 7, 1889.

Application filed July 31, 1888. Serial No. 281,496. (No model.)

To all whom it may concern:

Be it known that I, GURDON CONKLING, a citizen of the United States, residing at Glens Falls, in the county of Warren and State of New York, have invented new and useful Improvements in Magnetic Separators, of which the following is a specification.

This invention relates to certain improvements in magnetic separators, as set forth in the following specification and claims, and illustrated in the accompanying drawings, in which—

Figure 1 represents a plan or top view of part of a separator. Fig. 2 is a section in the plane xx , Fig. 1. Fig. 3 is a section in the plane yy , Fig. 1.

Similar letters indicate corresponding parts.

In the drawings, the letter A indicates a frame, in which are mounted three pairs of rollers, B B', B' B'', B'' B''' carrying a series of aprons, C C' C'', in such positions relatively to each other that the material discharged from the first apron, C, drops upon the second apron, C', and if more than two aprons are used the material from the second apron, C', drops upon the third apron, C'', and so on. A hopper, G, serves to feed material—such as comminuted iron ore—onto the apron C.

D E F are aprons which travel over rollers H in a direction at right angles to the aprons C C' C'' and in close proximity to the same. In the interior of each of the transverse aprons D E F are arranged magnets I, in proximity to those parts of said transverse aprons which are near to the conveying-aprons C C' C'', respectively. The magnets I can be permanent magnets or plates magnetized by the electromagnets K. As the iron ore passes beneath the transverse apron D a portion of the iron particles is attracted by the first magnet I and caused to adhere to said apron while the remaining ore is discharged upon the second apron C', and carried by the same beneath the transverse apron E, and as it passes beneath said apron the magnet I in this apron also attracts a quantity of iron particles, causing the same to adhere to said apron E. The same operation is repeated as the remaining ore passes beneath apron F. The waste discharges from the conveyer-apron C'' into the receptacle R, while the iron particles are

collected in receptacle N, one of which is shown in Fig. 2. Brushes L secure a separation of the iron particles from the transverse aprons, and chutes M serve to carry said iron particles into the receptacles N.

The shafts of the rollers H can be rotated by securing thereto pulleys O, and belts P may communicate motion to the pulleys Q, communicating with the rollers B B' B'''.

By having a series of conveying-aprons, C C' C'', and a corresponding series of transverse aprons, D E F, the operation of separating iron particles from non-magnetic parts can be carried on until the waste which discharges from the last of the conveying-aprons is practically free from iron, since any iron particles which should have escaped the attraction of the magnets of the apron D will be caught by the attraction of the succeeding magnets. Various grades of separation can also be attained by having the different magnets of varying intensity. By having, for instance, the magnet of the apron D of very slight intensity, so that its attractive power is weak, only pure iron particles will adhere to the apron D. By having the magnet of the apron E of greater intensity said magnet will attract iron particles, to which adhere, or which are surrounded by, objects not by themselves attracted by the magnet. By having the magnet of the apron F of still greater intensity it will attract iron particles containing still more matter not by itself attracted by the magnet. By placing the conveying-aprons one above the next, as shown, the waste of the first apron in being discharged upon the next apron is spread and turned over, so that the iron particles which on the first apron may have been covered up will be brought on the top and exposed to the action of the magnet on the next apron.

What I claim as new, and desire to secure by Letters Patent, is—

1. The combination, with a series of conveying-aprons running in the same direction, one above the next, as shown, of a series of transverse aprons, magnets secured in proximity to each of the transverse aprons, and suitable driving mechanism for actuating the aprons, substantially as described.

2. The combination, with a series of con-

veying-aprons running in the same direction, one above the next, as shown, of a like series of transverse aprons, a magnet secured in proximity to each of the transverse aprons, the 5 magnets of the different transverse aprons being of different intensities, and suitable drying mechanism for actuating the aprons, substantially as described.

In testimony whereof I have hereunto set my hand and seal in the presence of two subscr- 10
ing witnesses.

GURDON CONKLING. [L. S.]
